APPARATUS FOR GIVING ANESTHETICS

Jean Carré, Leers, France

Application June 25, 1934, Serial No. 732,349
In France July 18, 1933

3 Claims. (Cl. 128—191)

This invention relates to improvements in apparatus for giving anesthetics, with automatic oxygenation of the anesthetic atmosphere.

In known methods and apparatus for giving anesthetics in a confined atmosphere, the patient is made to breathe a mixture of anesthetic gases or vapors, air or oxygen, irrespectively of the quantity of air contained in the apparatus before the anesthesia begins, or of the quantity of moisture and carbon dioxide which is breathed out during the anesthesia. Also the known methods and apparatus do not in any special way permit of increasing the partial pressure of the anesthetic, and of bringing the proportion thereof in the mixture rapidly to a maximum. Also, by not taking into account the fact that the consumption of oxygen varies according to the degree of anesthesia, these known methods and apparatus do not provide for an addition of oxygen in the anesthetic mixture which is proportional to the quantity required by the patient, such quantity being also proportional to the volume of water vapour and carbon dioxide breathed out of the lungs.

One object of this invention is considerably to increase the proportion of anesthetic in the mixture given to the patient. Another object is to provide means for supplying automatically or semi-automatically to the mixture a quantity of oxygen proportional to the quantity of carbon dioxide and moisture expelled; the said means will preferably consist of oxygen generators and avoid the use of high pressure bottles which are heavy and cumbersome. Another object of this invention is to provide means for having a ready reserve of air expelled from the lungs and containing a big proportion of carbon dioxide; such reserve is used in case of necessity, avoiding the use of carbon dioxide pressure bottles.

Still another object of the invention is to have in the apparatus a determined direction of flow of gas which differs from the usual flow of gases in known apparatus. The direction of the flow of gases in the apparatus according to the invention is studied in view to permit of: (I) expelling the air contained in the apparatus before starting an operation; (II) obtaining in a receptacle a reserve of carbon dioxide as aforesaid; (III) proceeding to a control of the composition of the anesthetic at the entrance of the mask; in this manner one can immediately obtain in the mask a higher concentration of anesthetic than in other parts of the apparatus, or, inversely, instantaneously reduce the concentration of anesthetic in the mask. The mixture of gases being effected

at the entrance of the mask, and not in a receiver of the gases breathed out as in some known devices, the action of the anesthetic is either increased or diminished at the very instant the patient requires such action. On the contrary in most known devices the patient is obliged to breathe the atmosphere contained in a receiver before any modification in the anesthetic as required by the state of the patient can be effectively obtained. This can be a cause of serious trouble with some anesthetics.

In the appended drawings various forms of construction of the apparatus according to this invention have been illustrated:

Fig. 1 is a schematic view of a first form of the apparatus,

Fig. 2 shows a mask for giving anesthetics in confined atmosphere,

Fig. 3 shows an oxygen producing apparatus,

Fig. 4 is a plan view of the apparatus according to Fig. 1,

Fig. 5 is a plan view of a modification of the apparatus according to Fig. 1,

Fig. 6 is a front view of the apparatus of Fig. 5,

Fig. 7 is a side view of same,

Fig. 8 is a sectional view of a control tap for distributing the anesthetic,

Fig. 9 is a schematic plan view of a simplified apparatus for short anesthesia,

Fig. 10 is a view to Fig. 9 of the same apparatus during operation thereof,

Fig. 11 is a plan view of a similar apparatus, but for somewhat longer anesthesia.

The apparatus according to Fig. 1 essentially comprises a mask 1 of very gas-tight construction, a pipe 2 for breathing out, a valve 3, a bag-reservoir 4 for the atmosphere breathed-out, a cock 5 admitting into bag-reservoir 4, pipe 6 and suitable cocks 7 and 8 for regulating the flow of the gas to be breathed. The valves and the pipes are established to offer the minimum resistance to the breathing. 9 is a reservoir constituted by one or several cartridges or the like containing a chemical which gives forth oxygen by the action of water vapour and carbon dioxide. The chemical or chemicals contained in the reservoir 9 are such that the quantity of oxygen produced, which is in proportion with the carbon dioxide and water vapour absorbed, is in sufficient but not in excessive quantity for receiving the breath of the patient. A separate reservoir 10 containing chemicals which supply oxygen in case of need by the controlled action of water supplied drop by drop through apparatus 11, is also provided. Valves 12 and 13, and a cock 14

make it possible to expel all the air from the apparatus before utilization. A reservoir 15 for the anesthetic mixed in the breathed atmosphere is provided. 16 designates a similar reservoir for the anesthetic in case the first one is quite used up. A second bag-reservoir 17 provides for keeping in reserve an atmosphere containing a strong proportion of carbon dioxide in case the latter becomes insufficient in quantity in the mixture for breathing. A cock 18 controls the bag-reservoir 17. Another cock 19 suitably mounted permits of letting the patient breath independently of the apparatus at a moment's notice if required.

The apparatus functions as follows: First the operator gathers in the bag 17 a reserve of carbon dioxide. To this end the cock 18 is opened and cock 5 closed. The cocks 7 and 8 are operated so as to insulate from the circuit the oxygen regenerator 9, the atmosphere being directed 20 through the return pipe 6'. The simultaneous operation of the cocks 7 and 8, such that cock 7 is open when cock 8 is shut and inversely, may be effected by means of a single handle 20 shown on Fig. 1. By means of the reservoir 10 a quantity 25 of oxygen is produced sufficient for filling the bag 17. The patient is made to breathe into the bag 17, and as soon as the concentration of carbon dioxide in the atmosphere breathed in and out is such that the respiration becomes ample and quick, the cock 18 is closed at the end of an expiration, and the cock 5 is opened. The bag 17 now contains an atmosphere with a high proportion of carbon dioxide which may be useful later.

35 The operator then proceeds to produce in the apparatus an anesthetic atmosphere as pure as possible, by expelling all the air or oxygen which the apparatus contains. This result is obtained by opening the exhaust cock 14 and sending 40 through the apparatus a current of anesthetic from the reservoir 15. By the pressure of the anesthetic gas the valve 13 is closed against its seat and the current of gas expels all the air from the pipes and mask.

45 The bag 4 is filled with gas, then emptied by hand pressure, and filled again. The current of anesthetic gas expels the air from pipes 6 and 6', through the valve 12, and cock 14; the cocks 7 and 8 are then operated in order to send the current of anesthetic gas through the oxygen regenerator 9, the air from which is expelled through valve 12 and cock 14. The air thus being expelled from the apparatus, the cock 14 is manually closed and valve 12 is automatically closed and the anesthesia can begin.

55 When air is breathed out, the valve 3 is lifted. The anesthetic goes into the bag reservoir 4, the cock 5 of which is opened. When the patient breathes in, the valve 3 is closed whilst valves 12 and 13 are open, the exhaust pipe 14 being closed. The atmosphere which is breathed in passes through cock 8 and apparatus 9 where in some chemicals produce oxygen by the action of the steam and carbon dioxide of the expired atmosphere. These products, steam and carbon dioxide, are replaced by a proportional volume of oxygen. Therefore the oxygen is automatically regenerated in the course of respiration. If the quantity of oxygen obtained through the 60 apparatus 9 is not sufficient, the apparatus 10 may be used working in the manner described by admitting water from the reservoir 11; the oxygen produced by this apparatus is added to the oxygen produced by regenerator 9. The volume of oxygen 65 produced from 9 alone or with the help of 10 must

be just sufficient to maintain the respiration. The chemicals contained in apparatus 8 are disposed in such a manner that they interpose a small resistance to the current of gases which pass through them whilst giving the maximum contact 5 surface.

The regenerated atmosphere, containing the necessary quantity of oxygen, passes through valves 12 and 13 and reaches the mask. The cock 18 of the bag 17 is kept closed. When a further 10 quantity of atmosphere is expired the valve 3 opens whilst valves 12 and 13 are closed and the operation is continued as aforesaid.

If the proportion of oxygen is still too much in the expired atmosphere, the handle 20 is operated so as to divert more or less of the atmosphere through the pipe 6' instead of the apparatus 9.

If the quantity of carbon dioxide is insufficient in the atmosphere to be breathed in, one 20 may use the carbon dioxide mixed with oxygen contained in the bag-reservoir 17 by opening the cock 18. This operation will rarely be necessary as the bag reservoir 4 always contains a certain proportion of carbon dioxide when the pipe 6' is 25 correctly used as aforesaid.

If the anesthesia becomes too serious one may let the patient breathe fresh air through cock 19. When the bag-reservoir 4 becomes empty on account of the absorption of anesthetic by the lungs, 30 a fresh quantity of the gas may be introduced by the reservoir 15, and when the latter becomes exhausted, the reservoir 16 may be used without disconnecting 15. The absorption of the anesthetic by the patient decreases with the progress 35 of the anesthesia to become null when the anesthesia is complete.

The apparatus which has been described with reference to Fig. 1 can be used with any anesthetic which is not modified by the contact with 40 the chemicals used for regenerating the oxygen, for instance with nitrogen protoxide, ethylchloride, and the like.

If the concentration of nitrous oxide in the inhaled atmosphere is too great, it produces saturation of the blood which renders the anesthesia 45 dangerous. The nitrous oxide is already greatly concentrated in the inhaled atmosphere and this should not be increased to a degree to result in blood saturation with a consequent dangerous 50 condition; consequently if the anesthesia tends to go too far, air must be given through the cock 14; such air dilutes the anesthetic, lowers the partial pressure of protoxide in the mixture and reduces the anesthesia. The same result may be obtained 55 by setting apparatus 10 in action to add pure oxygen to the anesthetic.

The method of giving anesthetics as described above is effected in a confined atmosphere and consequently a perfectly gastight mask must be 60 used, of a type illustrated by way of example in Figs. 1 and 2. The mask illustrated by Fig. 1 comprises a pneumatic tire or pad 21 which ensures gas-tight contact around the mouth and nose of the patient, a chin-piece 22, and straps 23 65 suitably disposed and tensioned for maintaining the whole mask well applied on the face of the patient. The eyes of the patient remain free, which permits of examining them in the course of the operation.

The mask illustrated in Fig. 2 covers entirely the face of the patient and is attached by straps 24; it comprises eye-holes 25 and a chin-piece 26. A finger tube 27 opened at its end 28 allows the 70 surgeon to examine the eyes.

Fig. 3 illustrates an oxygen regenerating apparatus which does not contain the chemicals in cartridges but has the advantage of allowing easy renewal of the chemicals used for producing oxygen from carbon dioxide and water, after each operation. The apparatus shown in perspective view comprises a box 29 containing elements 30 of cylindrical or parallelopipedic shape, made of gauze wire or similar material and disposed in successive layers. These elements are impregnated with the oxygen regenerating product. The sides 31 and 32 of the box are left empty to allow easy filling of the elements 30. When the apparatus has been charged, the side panels 33 and 34 are fitted in, the two other sides of the box 29 being fixed, and the top and bottom sides of the box being formed of wire gauze for the flow of gas. The box 29 is fitted inside a casing 35, which comprises two removable covers 37, one on each side, each cover having a filtering layer 38, removable and formed of asbestos, another filter 39 of asbestos-fibre and a pipe connection 40. Although this oxygen-regenerating apparatus provides a very great surface of contact for the gas with the chemicals it offers very little resistance to the flow of the breathed atmosphere. The general shape of the apparatus is very flat to provide for better cooling.

Fig. 4 shows the same apparatus as in Fig. 1, but in plan view, as disposed for an operation on a table or horizontal support 40; the different parts of the apparatus are indicated by the same reference numerals as in Fig. 1.

The apparatus illustrated by Figs. 5 to 8 is devised specially for the use of nitrogen protoxide, with the use of oxylith as oxygen regenerating agent. Oxylith, as here referred to, as a chemical oxygenating agent, is an alkaline peroxide having the property of disengaging or evolving oxygen under the action of carbonic acid and the water vapor contained in the atmosphere exhaled by an individual. Among such alkaline peroxides may be mentioned activated sodium peroxide, potassium and sodium trioxide and potassium and sodium pentoxide, all of which are capable of use after the oxygenating power has been reduced. These chemical agents absorb the carbonic acid and water vapor contained in the exhaled atmosphere and then evolve sufficient oxygen to maintain respiration, but not to such great extent as to reduce the anesthetic proportion in the mixture inhaled.

The apparatus comprises a supporting cradle 61 secured to the edge of the operation table 62. The cradle 61 has a shape adapted to receive the oxylith cylinder or reservoir 63. At one end of the cylinder is connected a pipe 64, by means of a winged-nut 65. At the other end of the cylinder 63 is connected the pipe 66 by means of the winged-nut 67. A collar 68 fixed to or integral with the cradle 61 carries the central pipe 69 leading to a gas-tight mask. The pipe 69 leads from a three-way cock 70 which is illustrated in detail and in cross-section in Fig. 8. The cock 70 is connected on the one side to the pipe 64 and on the other side to the pipe 66.

A bottle 71 of nitrogen protoxide is connected to the central pipe 69 by means of the connection 72 and winged nut 73. A bottle 74 containing a mixture of oxygen and carbon dioxide is also connected to the pipe 69 by means of the tubing 75 and winged nut 76. This bottle is here shown by way of example in lieu of the carbon dioxide bag reservoir, and additional oxygen producing apparatus of Fig. 1.

A pipe connection 77 provided with a valve 78 forms a by-pass between pipes 64 and 68 near the three-way cock 70. A bag-reservoir 79 for the reserve of anesthetic is connected to pipe 64. A cock 80 opening into the air, and valves 81 and 82, are provided for expelling the air from the apparatus and for obtaining a high concentration of anesthetic.

The three-way cock 70 illustrated separately in Fig. 8 comprises a cylindrical casting 83 at the bottom of which is connected pipe 69. Inside the casting 83 fits a plug 84 which is milled on a portion of its circumference to leave only the solid part 85 extending near the bottom of the casting. The casting 83 comprises, in two places of the circumference thereof, perforations 86 and 87. Two chambers 88 and 89 formed in the wall of the casting receive the ends of pipes 64 and 66. An axial pin 90 and a handle 91 are provided for operating the cock. By appropriately turning the plug the perforations 86 and 87 can be gradually opened or closed. It will, of course, be understood that each of the valves 7 and 8 of Fig. 1 may be arranged and constructed in the form disclosed in Fig. 8, whereby graduated opening of one of said valves accompanies the corresponding graduated closing of the other, and vice versa.

This apparatus functions as follows: the operator first makes certain that there is in the apparatus an anesthetic atmosphere which is as pure as possible, by expelling the air or oxygen from the apparatus. This result is obtained by opening the exhaust pipe 80 and sending a flow of protoxide gas through the apparatus. The valve 82 is closed by the pressure of the gas and the cock 70 is operated so as to close pipe 64. The flow of gas expels the air from the tube 69 and the mask. The cock 70 is then operated so as to close the pipe 66, but to open pipe 64 and the flow of gas expels the air from by-pass 77 and pipe 64. The bag 79 is filled with gas, then emptied by hand pressure, and filled again. The gas passes through the oxygen regenerating cylinder 63 to expel the air therefrom and through the pipe 66 from which the air escapes by the valve 81 and the exhaust pipe 80 which can then be closed. The anesthesia operation can now be performed under favourable conditions.

The cock 70 is turned so that the pipe 64 is closed whilst the pipe 66 is opened; by expiration the air passes through the by-pass 77 in which the valve 78 opens, and fills the bag 79; by inspiration the valve 78 is closed, whilst the valves 81 and 82 are open, the cock 80 being of course closed. The atmosphere from the bag 79 passes from the pipe 64 into the reservoir 63 wherein the chemical produces oxygen from the carbon dioxide and water of the atmosphere breathed out. The volume of oxygen thus produced is in a certain proportion with the volume of carbon dioxide and vapour breathed out. The regeneration of oxygen is effected automatically. The recomposed breathing atmosphere returns into the mask through the pipe 66, valves 81 and 82, cock 70 and pipe 69. By a further expiration, valve 82 closes whilst valve 78 opens and the same operation is performed. If the quantity of oxygen produced in the reservoir 63 is insufficient, one must use the mixture of oxygen and carbon dioxide contained in reservoir 74, and determine the proportions properly.

If the quantity of oxygen from the reservoir 63 becomes too high in proportion to the protoxide, cock 70 is turned so as to close partially or totally the pipe 66. In this manner part of the

aspired atmosphere or the whole of it does not pass through the reservoir 63. In this latter case the atmosphere is breathed out into the reservoir 79 through the pipe 64 and is breathed in again directly through the cock 70 and the pipe 69 without passing through the reservoir 63 or the pipe 66. By simply turning the handle 91 one may control the openings of pipes 64 and 66, and the action of the reservoir 63 for obtaining a smaller or higher proportion of oxygen, and inversely of carbon dioxide in the anesthetic.

If on the other hand the proportion of carbon dioxide in the anesthetic atmosphere is insufficient, one may use the reserve of carbon dioxide 15 and oxygen contained in bottle 74, or simply reduce the proportion of oxygen.

If the anesthesia becomes too deep, one may open communication with the outer atmosphere near the mask, or else one may dilute the protoxide of nitrogen in the mixture by opening the cock 80; the air which thus breathed in dilutes the protoxide.

The apparatus illustrated by Figs. 9 to 11 is devised specially for short anesthesia, such as is required for instance for extracting a tooth, incising an abscess, and the like. Although this apparatus is destined to be used specially with nitrogen protoxide and oxyliith with other chemicals or not, one may also use same with other anesthetics such as ethyl chloride, and the like.

For these anestheses of short duration, it is required to obtain complete anesthesia, by means of a high concentration of anesthetic in the atmosphere to be breathed, the anesthesia being stopped as soon as this result is obtained. The maintaining of the anesthesia not being required in this case, the parts of the apparatus designed to prolong the anesthesia can be dispensed with. Namely, the members (bags, bottles) for having a reserve of carbon dioxide and of oxygen and the circuit with the valves may be dispensed with. However, with this apparatus can be used sparklets of nitrogen protoxide, oxygen and carbon dioxide which allow to prolong slightly the anesthesia if required.

The pipes are made as short as possible, and the dead space, which corresponds to the volume of gas remaining after each expiration between the lips of the patient and the oxygen regenerator, is almost null; the purification of the gas is sufficient at each breath without the use of the complete circuit with valves. The apparatus thus simplified for giving anesthetics for a little while is therefore of reduced weight and volume, and easily portable.

The apparatus of Figs. 9 and 10 essentially comprises: a mask 92 with pneumatic pad 93 and rings 94 for attaching the mask against the face, a short pipe 95 connecting the mask with a three-way cock 96 having an opening 97 to the free air. The plug of the cock 96 comprises a full portion 99 and a hollowed portion 98; the operation of the cock is effected by a handle or wheel or any equivalent means. A tube 100 connects the cock 96 to the oxygen regenerating cartridge 101 which functions for a few minutes. To the tube 100 is connected a small tube 102 having a threaded end on which can be adapted a bottle 103 of the sparklet type, containing nitrogen protoxide. The sparklet is shown with the nozzle disposed in the middle of the cylindrical body which facilitates the manipulation thereof. The oxygen regenerating cartridge 101 communicates on the one side with the tube 100 and on

the other with the bag-reservoir 104 for anesthetic atmosphere.

The oxygen regenerating cartridge which is here shown for oxyliith, contains a central disc having a certain number of holes formed in a circle for the passage of the gas, while the central portion of said disc is full. This arrangement obliges the gas passing through the cartridge to come well into contact with the oxygen regenerating product, and ensure maximum efficiency. Wire gauze or filters of glass-wool or of asbestos-wool retain the chemical inside the cartridge. The cartridge 101 having been, in course of manufacture, filled with nitrogen protoxide, contains no air. The bag reservoir 104 is emptied before being adapted on the apparatus.

This apparatus operates as follows: the cock 96 is turned so as to close the tube 100; the sparklet is then screwed on and the nitrogen protoxide fills the bag 104 through the cartridge 101; the cock 96 is in the position illustrated by Fig. 9. The mask is applied against the face of the patient. At this stage only the cock 96 still contains air. To commence the operation of giving the anesthetic, the operator turns the cock in the direction of the arrow Fig. 9. By this operation there is a point when the plug closes the pipe 95 and leaves open the tube 100 and the opening 97, as is illustrated in Fig. 11. During the very short time that this position occurs, the protoxide of nitrogen, still under pressure in the bag 104, expels the air from the tube 100 and from the cock through the opening 97. The plug being turned further in the same direction the pipe 95 is opened whereas the opening 97 is closed. This position is maintained for giving the anesthetic and is illustrated by Fig. 10. The reservoir-bag 104 is thereby in communication with the mask. The gas breathed in and breathed out has its oxygen regenerated by passing through the cartridge 101 in the manner aforesaid.

As soon as the anesthesia is complete, the operator takes the mask away from the face of the patient and immediately performs the short, painful operation. If the anesthesia must be kept on for a short time, it will however be necessary to stop it as soon as the cartridge 101 is exhausted. If on the other hand the quantity of carbon dioxide is insufficient the anesthesia must be stopped.

In the case of operations lasting somewhat longer than those contemplated for this last described embodiment of the apparatus, one may use the same apparatus, but with the help of extra gas bottles, as illustrated by Fig. 11 of the drawings. If the quantity of carbon dioxide, or of nitrogen protoxide, or of oxygen is insufficient in the mixture, one may with this apparatus immediately use an extra sparklet of bottle containing one of these gases respectively.

With reference to Fig. 11, a pipe of small gauge, 105, is connected to tube 100. The pipe 105 leads to three branchments 106, 110, 114, respectively leading to three cocks 107, 111 and 115, to a bag-reservoir respectively 108, 112, and 116, and to a respective sparklet. The first sparklet 109 contains anesthetic. The second sparklet 113 contains oxygen, and the third 70 sparklet 117 contains carbon dioxide. When these sparklets are opened the respective bag-reservoirs 108, 112, and 116 contain the respective gases, and by means of the respective cocks 107, 111, and 115 these gases can be sent 75

into the anesthetic apparatus according to the requirements and according to the required proportions. The additional sparklets, cocks and bags are laid on a table near to the main apparatus and under the immediate control of the operator.

If the sparklets have a needle valve instead of a tin capsule which has to be pierced, the individual reservoirs 108, 112, and 116 can be dispensed with, and the required quantity of carbon dioxide, nitrogen protoxide or of oxygen can be sent directly into the main reservoir 104.

Having now fully described my said invention, what I claim and desire to secure by Letters Patent, is:

1. An apparatus for giving anesthetics in a confined atmosphere, comprising in a closed circuit, successively in the direction of the flow of gas: a main circuit and a shunt circuit, cocks in each circuit after the branchment of said shunt circuit, a common means for operating said two cocks whereby the one cock is closed when the other is opened, and whereby said cocks are opened and closed progressively, an oxygen regenerating apparatus in said shunted portion of the main circuit, an oxygen producing apparatus connected to said shunt circuit, a cock beyond the shunt circuit allowing communication with the free air, and placed immediately before a connection with a source of anesthetic under pressure, valves permitting the said determined direction of flow of gas, a connection between the said closed circuit and the mask, and a cock for closing said last mentioned connection and for communicating said mask with the free air.

2. An apparatus for giving anesthetics in a confined atmosphere, comprising in a closed circuit, a connection, with a cock, to a bag-reservoir for a reserve of pure anesthetic atmosphere, a shunted portion of the main circuit and a shunt circuit, cocks in each circuit after the branchment of said shunt circuit, a common means for operating said two cocks whereby the one cock is closed when the other is opened, and whereby said cocks are opened and closed progressively, an oxygen regenerating apparatus in said shunted portion of the main circuit, an oxygen producing apparatus connected to said

shunt circuit, a cock beyond the shunt circuit allowing communication with the free air, a bag-reservoir for a reserve of expired atmosphere and sources of anesthetic under pressure connected to the main circuit immediately before the connection from the said main circuit to the mask, and means for closing said last mentioned connection and for communicating said mask with the free air.

3. An apparatus for giving anesthetics in a confined atmosphere, including an air excluding mask, a single conduit leading therefrom, a closed circuit conduit in communication with the single conduit remote from the mask, a control valve in the single conduit operable to place the mask in communication with the atmosphere or with the closed circuit conduit at will, automatically opening valves in the closed conduit permitting gaseous flow in one direction only, an anesthetic gas container in communication with the closed circuit, a manually controlled air vent valve in the closed circuit beyond the container in the direction of gaseous flow, an anesthetic gas reservoir in the closed conduit beyond the air vent valve, and an automatically opening valve in the closed circuit conduit between the air vent valve and anesthetic gas reservoir, whereby on opening the atmospheric vent valve and closing the control valve the anesthetic gas from the reservoir may be forced through the closed circuit conduit to clear the latter of air and to charge the anesthetic gas container, said anesthetic gas container being open to the exhalations of the patient in the use of the apparatus for giving anesthetics, a by-pass in the closed conduit beyond the anesthetic gas container in the direction of gas flow, and simultaneously and oppositely acting valves controlling the closed conduit and by-pass conduit to direct the gas flow wholly through the by-pass conduit, wholly through the closed conduit, or partially through each, and an oxygen regenerating apparatus in the by-pass conduit, whereby upon opening the by-pass conduit oxygen is automatically regenerated during the course of respiration in the use of the apparatus.

JEAN CARRÉ.
